CHILD'S BARBER APRON, OR SIMILAR ARTICLE

Miriam L. Bush, Box 231, High St.,
Three Bridges, N.J. 08887

Continuation of design application Ser. No. 1,891, Apr. 14,
1966. This application July 27, 1966, Ser. No. 3,224

Term of patent 14 years

(Cl. D86—10)

FIG. 1

FIG. 1 is a front perspective view of a child's barber apron, or similar article showing my new design in wearing position; and

FIG. 2 is a top plan view of the cape shown in FIG. 1 in a flat undraped position.

This is a continuation of my copending application Ser. No. D. 1,891, filed Apr. 14, 1966, and now abandoned.

I claim:

The ornamental design for a child's barber apron, or similar article, substantially as shown and described.
